UNITED STATES PATENT OFFICE

101,141

DESIGN FOR A WINE BARREL STAND

Anthony Sanfilippo, San Francisco, Calif.

Application March 4, 1936, Serial No. 61,466

Term of patent 14 years

To all whom it may concern:

Be it known that I, Anthony Sanfilippo, a citizen of the United States of America, residing at San Francisco, in the county of San Francisco and State of California, have invented a new, original, and ornamental Design for a Wine Barrel Stand, of which the following is a specification, reference being had to accompanying drawing, forming a part thereof.

The figure is a perspective view of the article, showing my new design.

I claim:—

The ornamental design for a wine barrel stand, substantially as shown.

ANTHONY SANFILIPPO.
